UNITED STATES PATENT OFFICE.

HARRY A. INMAN, OF AMSTERDAM, NEW YORK.

MACHINE FOR BAILING PAPER PAILS.

1,104,803.

Specification of Letters Patent. Patented July 28, 1914.

Original application filed May 3, 1911, Serial No. 624,812. Divided and this application filed December 8, 1911. Serial No. 664,608.

To all whom it may concern:

Be it known that I, HARRY A. INMAN, a citizen of the United States, residing at Amsterdam, county of Montgomery, and State 5 of New York, have invented certain new and useful Improvements in Machines for Bailing Paper Pails, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a view in front elevation of a paper-pail forming and 20 bailing machine containing my improved bailing-mechanism. Fig. 2 is a side elevation of the same. Fig. 3 is a horizontal cross-section of the same taken on the broken line 3—3 in Fig. 2, showing in top plan the 25 bed-plate of the machine and certain of the operating-mechanisms. Fig. 4 is a horizontal section taken on the broken line 4—4 in Fig. 2, and showing in bottom plan the bed-plate and various link and lever connections 30 mounted upon the underside thereof. Fig. 5 is a view in front elevation of the parts shown in Fig. 4. Fig. 6 is a view in front 35 elevation showing certain of the mechanisms on a larger scale than in Fig. 1. Fig. 7 is a view in side elevation showing certain of the mechanisms on a larger scale than in Fig. 2. Fig. 8 is a horizontal cross-section taken through the partly formed pail and the forming-mechanism. Fig. 9 is a similar 40 view showing the folding operation completed and the bail-ends driven through the side-wings preparatory to clenching said ends. Fig. 10 is a similar view partly broken away, showing the bail-end clenched. Fig. 11 is a plan view of the blank from 45 which the pail is formed.

This application is a division of an application filed by me May 3, 1911, Serial No. 624,812, for a machine for forming and bailing paper-pails.

The present invention relates more particularly to a machine for attaching bails to

paper-pails having lapping side-wings, such as the ordinary paper oyster-pail.

The principal object of the invention is to 55 attach to the lapping side-wings of such a paper-pail a preformed wire bail, without thereby penetrating the main body-wall of the pail.

Other objects will appear in connection 60 with the following description.

Referring to the drawings wherein the invention is shown in preferred form, 1 represents the base of the machine and 2, a bed-plate or table fixedly mounted thereon and 65 adapted to support the blank 3 (shown in Fig. 11) preliminary to the folding operation, and to coöperate with the other mechanisms in folding the blank to proper form. The bed is provided with an aperture 4, 70 down through which the blank is adapted to be forced by a head or plunger 5, vertically reciprocatory in slideways in an overhanging arm 6, erected from the base of the machine. A yielding bed 7 is supported by 75 means of a spring-post 8 within the opening 4 in the bed-plate in line with the plunger-head, 5, said yielding bed being adapted to support the central part of the blank which forms the bottom of the pail, and which is 80 held clamped between said yielding bed and the plunger-head, 5, during the folding operation.

The plunger-head, 5, is mounted upon the lower end of a toothed slide-rack, 9, which is 85 engaged by a pinion, 10, fixed upon the same shaft with a pinion, 11, adapted to be engaged by a toothed rack on the crank-rod, 12, connected with a crank-disk, 46, operated in a manner hereinafter described, whereby 90 a reciprocating vertical movement is imparted to the plunger-head 5. As the plunger-head, 5, descends through the opening, 4, in the bed-plate, the bottom of the box is clamped between said plunger-head and 95 the yielding bed, 7, and the blank is drawn down within the aperture, 4, the walls of which serve to upturn the side-portions of the blank and partly fold the same to approximately the cross-sectional form shown 100 in Fig. 8. A pair of side-wings or flaps, 14, are thus formed on each side of the pail, which wings require to be folded in from the position shown in Fig. 8 to that shown in

Fig. 9, so that the wings of each pair shall lap each other. This is accomplished toward the latter part of the descending movement of the plunger-head, 5, by means of 5 two pairs of oscillatory arms, 15, one of each pair being mounted upon a rock-shaft, 16, and the other of each pair upon a parallel rock-shaft, 17, which rock-shafts have fixed thereon, respectively, rocker-arms, 18, which 10 project into the path of the descending yielding bed 7. The final descending movement of the bed, 7, forces down the rocker-arms, 18, thereby rocking the shafts, 16, and 15 17, to force the arms, 15, inward to fold the wings, 14, of the sides of the pail, as shown in Fig. 9. This completes the folding or shaping of the pail, which can be removed from the machine by raising the plunger-head, 5, and stripping the folded pail therefrom.

In adapting the machine for automatically attaching the wire bails to the pails, I provide a carrier and holder for the bail in the form of a slide, 19, reciprocatory in 25 slideways, 20, on the bed-plate, and having a pair of arms, 22, adapted to freely receive therebetween the folded pail, the body of the slide and said arms being formed with seats to receive a wire bail, 90, which can be 30 placed thereon by hand. The seats for the ends of the bail on the arm, 22, are undercut at, 21, so as to overhang the ends of the bail. Suitable means which will be presently described are provided for automatically 35 imparting to the slide, 19, inward and outward movements at proper times. The inward movement of the slide, 19, is so timed that the bail-ends are brought opposite the lapping portions of the side-wings, 40 14, on the respective sides of the box upon the completion of the folding of said side-wings, and when thus located each of said bail-ends is engaged by a plunger, 23, which drives the end of the bail through the lapping 45 side-wings and into an opening, 24, in a stationary upright plate, 25, which occupies a position between the body of the box and the lapping side-wings thereof. As the bail-end is thrust through 50 the lapping side-wings, 14, it is engaged by a clenching-arm, 26, which bends back upon itself the end of the bail to form a hook thereon, as shown in Fig. 10, said hook being flattened or closed by compression between 55 the clenching-arm, 26, and the plunger, 23, during the final movement of said plunger. The clenching arm or member, 26, is movable along the outer side of the upright plate, 25, in the space between said 60 plate and the lapping side wings of the box. The clenching arm, 26, is fixed upon a rock-shaft, 28, upon which shaft is also fixed a stud, 30, located in the path of a cam or wedge-shaped member, 31, in fixed relation to 65 the plunger, 23, so that as the plunger, 23,

moves inward to force the bail-end through the side-wings of the pail, the cam, 31, will be forced against the stud, 30, causing a rocking movement of the rock-shaft, 28, whereby the clenching arm, 26, is moved across 70 the path of the inserted end of the bail, serving to clench the same as above described. The thickness of the clenching arm, 26, and the upright folder, 25, is sufficient to prevent the end of the bail from 75 penetrating the side-wall, 32, of the body of the pail, as will be seen in Fig. 9. The stock itself of the lapping side-wings affords sufficient support to the bail-wire to enable the clenching-arm, 26, to bend the end of the 80 bail-wire to hook-form as above described. When the bailing operation has been completed, the plungers, 23, with their wedges, 31, are withdrawn, permitting the clenching-arm to be returned to its initial position 85 by means of the coil-spring, 33; the slide, 19, is moved back to its outermost position; and the plunger-head, 5, is raised, carrying upward with it the folded-and-bailed pail. As the rocker-arms, 18, are relieved from pressure by the rising of the bed, 7, the wing-folders are rocked back by means of a coil-spring, 34, which connects together a pair of 90 rocker-arms, 35, fixed upon the respective rock-shafts, 16 and 17.

As a means for accomplishing the necessary movements of the slide, 19, and plunger, 23, in proper time-relation with the descending and ascending motions of the plunger-head, 5, I provide connections whereby 100 all of said mechanisms are driven from a common shaft 37. A pinion, 38, on the shaft, 37, engages a gear-wheel, 39, on a shaft, 40, rotatively mounted in bearings, respectively, on the bed of the machine, and 105 on the upper end of the stationary post 47. The gear-wheel, 39, meshes with a gear-wheel, 41, which runs loosely on a shaft, 42, which shaft is rotatively mounted in bearings on the frame of the machine. In fixed 110 relation to the gear-wheel, 41, is one member, 43, of an intermittent clutch, the other member, 44, of which is feathered upon the shaft, 42, and is forced into engagement with the clutch-member, 43, by means of a coil-spring, 45. When the clutch-member, 44, is held in engagement with the clutch-member, 43, by means of said coil-spring, the rotary movement of the gear, 41, will be transmitted to the shaft, 42, upon the end of 115 which shaft, 42, is fixed a crank-disk, 46, with which is connected the crank-rod 12. The movable clutch-member, 44, is at certain times forced out of engagement with the clutch-member, 43, by means of a lever, 50, fulcrumed at, 51, upon a fixed bracket, 52, and having on its upper end a yoke, 53, engageable with the hub of the clutch-member, 44, and on its lower end a stud or cam-follower, 55, adapted to be engaged by a 120 125 130

cam, 56, fixed upon the shaft 40. The cam, 56, is so shaped that upon the completion of the downward movement of the plunger-head, 5, the clutch is held open to permit the 5 plunger-head, 5, to remain stationary during the bailing operation.

A vertical rock-shaft, 57, is mounted at its lower end in a bracket, 58, projecting from the post, 47, and at its upper end in a bracket, 59, projecting from the base of the machine, said shaft having fixed thereon a rocker-arm, 60, upon the end of which is a cam-follower, 61, which occupies a cam-groove, 62, in a cam-wheel, 63, fixed upon the shaft, 40, whereby rocking movements are imparted to said shaft 57. A rocker-arm, 64, on the upper end of the shaft, 57, is connected by a short link, 65, with one end of a link, 66, the other end of which is connected with a lever, 67, fulcrumed at, 68, upon the underside of the bed-plate of the machine, and having a slotted end adapted to engage a stud or pin, 69, fixed to one of the plungers 23. The link, 66, is also connected with one end of a lever, 70, fulcrumed at, 71, upon the underside of the bed-plate, and having its other end connected by a link, 72, with one end of a lever, 73, pivotally connected at, 74, with a slide, 75, movable in a 30 slideway on the underside of the bed-plate. The other end of the lever, 73, is connected with one end of a lever, 76, fulcrumed at, 77, on the underside of the bed-plate, and having a slotted end, 78, adapted to engage 35 a stud or pin, 79, fixed to the other plunger 23. The lever, 73, being mounted upon the slide, 75, a movement of the link, 72, will impart a bodily movement not only to the slide, 75, but to the lever, 73, which is however 40 free to rock upon its pivot, 74, to accommodate itself to the arc of movement of the end of lever, 76, with which it is connected. A pair of cam-shaped plates, 80 and 81, are mounted upon the slide, 75, in 45 position to at certain times engage one arm of an angle-lever, 82, fulcrumed at, 83, upon the underside of the bed-plate, and having its other arm slotted and adapted to engage a stud or pin, 84, fixed to the slide, 19, which 50 stud or pin, 84, projects down through a slot, 85, in the bed-plate.

The arms of the several levers are so proportioned as to accomplish the several movements in the order above described, and the 55 cam-shaped plates, 80 and 81, are so located as to provide lost-motion in the operation of the lever, 82, at the beginning of the inward movement of the slide, 19, to allow a sufficient interval for the folding operation 60 before the bail is moved into position for the bailing operating, and at the beginning of the outward or return movement of the slide, 19, to allow the necessary interval for the withdrawal of the plungers, 23, before 65 the return movement of the slide begins.

I make no claim herein to the pail-forming mechanisms, nor to the combination of pail-forming and bailing mechanisms herein shown and described, the same being claimed in said original application of which the present application is a division. 70

For the purposes of the present invention the paper-pail may be formed and placed in position in any known manner wherebv it is adapted for the action of my improved 75 bailing-mechanism above described.

What I claim as new and desire to secure by Letters Patent is—

1. In a machine for bailing paper-pails or the like, and in combination, a form adapted 80 to be inserted within the body of the pail; and bail-inserting-and-clenching mechanism comprising in part a member interposed between the body of the pail and its lapping side-wings, said member being coöperative 85 with said form to support the body of the pail thereupon, and coöperative with said wings to support the same against the thrust of the bail-inserting mechanism.

2. In a machine for bailing paper-pails 90 or the like, and in combination, means for holding in position a formed pail having lapping side-wings; a plate adapted to occupy a position between the body of the pail and said lapping wings and provided 95 with an opening to receive the end of the bail; a bail-carrier movable to and from a position opposite said side-wings; means for driving the ends of the bail through said side-wings when the bail-carrier is opposite 100 thereto; and means for bending the ends of the bail.

3. In a machine for bailing paper-pails or the like, and in combination, a form 105 adapted to be inserted within the body of the pail; and bail-inserting-and-clenching mechanism comprising in part a member interposed between the body of the pail and its lapping side-wings, said member being coöperative with said form to support the 110 body of the pail thereupon, and coöperative with said wings to support the same against the thrust of the bail-inserting mechanism, and in part clenching-mechanism movable in the space between the body of the pail 115 and said lapping side-wings.

4. In a machine for bailing paper-pails or the like, and in combination, means for supporting a formed pail having lapping side-wings; a plate adapted to occupy a position between the body of the pail and said lapping side-wings, and provided with an opening to receive the end of the bail; means for forcing the end of the bail through said lapping side-wings; and a 120 clenching-member movable in the space between said plate and said lapping side-wings.

5. In a machine for bailing paper-pails or the like, and in combination, means for 130

holding in position a formed pail having lapping side-wings; a plate adapted to occupy a position between the body of the pail and said lapping wings, and provided with an opening to receive the end of the bail; a bail-carrier movable to and from a position opposite said side-wings; means for driving the ends of the bail through said side-wings when the bail-carrier is opposite thereto;

and a clenching-member movable in the space between said plate and said lapping side-wings.

In testimony whereof, I have hereunto set my hand this 23 day of November, 1911.

HARRY A. INMAN.
